UNITED STATES PATENT OFFICE.

ALFRED J. SIGNOR, OF ELKHART, INDIANA, ASSIGNOR TO GEORGE L. PUTERBAUGH AND JESSE C. PUTERBAUGH, OF ELKHART, INDIANA.

BEER OR LIQUID BOTTLING DEVICE.

No. 796,093.

Specification of Letters Patent.

Patented Aug. 1, 1905.

Application filed April 23, 1904. Serial No. 204,566.

To all whom it may concern:

Be it known that I, ALFRED J. SIGNOR, a citizen of the United States, residing at Elkhart, in the county of Elkhart and State of Indiana, have invented new and useful Improvements in Beer or Liquid Bottling Devices, of which the following is a specification.

My invention relates to an improvement in liquid-bottling devices, the object being to provide a neat, simple, and inexpensive mechanism of the above character which can be quickly connected and disconnected and one which will accomplish the desired result with ease and facility.

A further object is the provision of a device of this nature which can be easily cleaned in case of need.

Another object is the provision of a suitable adjustable support for the liquid-containing receptacle, together with means for rotating the receptacle so supported to permit of its being emptied or the liquid contained therein decanted, and while so decanting or emptying to replace the liquid with air at atmospheric pressure to prevent the formation of a vacuum within the receptacle. The rotation of the receptacle in one direction or the other will permit or prevent the escape of liquid therefrom.

My invention further consists in certain other novel features of construction and combinations of parts, such as will be more fully described hereinafter and particularly pointed out in the claims.

In the accompanying drawings, Figure 1 is a view in cross-section of my improved decanting or racking apparatus; and Fig. 2 is a similar view showing the entire device, including the elevating mechanism.

My invention comprises a portable frame consisting of the feet or bases A, from one end of which rise the uprights B, preferably of channel-iron and U-shaped in cross-section, the open faces of the uprights facing each other. Cross-braces C and D connect the upper and lower ends, respectively, of the uprights or standards to strengthen and afford rigidity to the frame.

The elevator consists of the horizontal arms E, their outer or free ends being reduced or beveled, as shown at 1, the arms adapted to be received between the feet or bases A, which latter are more sharply inclined at their outer ends, as at 2, than are the arms E, the feet or bases each being pro-

vided with a suitable depression, such as T, located between the chocks or projecting lugs S to receive the keg or barrel, the chocks preventing the accidental displacement of the receptacle. The feet, it will be noted, are connected to the outer faces of the standards, whereas the arms E project from the inner faces thereof, this arrangement permitting the arms to be received between the feet when the elevator is in its lowermost position, the abrupt incline at the ends of the feet extending above the gentler inclines or bevels at the ends of the arms. Journaled in the arms and extending therebetween are the supporting-rolls N N, the material of which the arms are formed being cut away, as at 3, to give clearance to the keg or barrel supported on the rollers. The rear ends of the arms are provided with guides F, received within the channeled faces of the standards, each guide carrying two or more rollers G G, pivotally secured or journaled thereto, the rollers engaging the sides of the standards, which form tracks or ways therefor and being of a diameter greater than the width of the guides, thereby preventing the frictional engagement of the guides and standards. A plurality of rollers are employed on each guide in order that there may be no pivotal rocking movement of the elevator and insure a precise upward and downward movement only. A cross-rod H extends between and is secured to the guides to retain them in alinement at all times, and secured to this cross-rod are the ropes, cables, or other flexible connections I, the opposite ends of which are secured to the drum of a windlass J, journaled in and extending between the upper ends of the standards and housed beneath the channel-iron cross-brace C. The ends of the windlass project through the standards and are provided with ratchet-toothed wheels K, the teeth of which are adapted to be engaged by the free end of a pawl L, suitably pivoted to the standards, the windlass being rotated in one direction or the other by means of the cranks M to raise or lower the elevator.

The arms E are adapted to receive and support the keg, barrel, or other receptacle from which the liquid is to be racked, and in placing it thereon the arms are first lowered until they rest between the feet A, the latter being slightly higher than are the arms. The barrel or keg is then rolled up the incline 2 of the

feet until it rests in the depression T, whereupon the elevator is raised and the keg is lifted up on the rollers N N. The dotted lines at the bottom of Fig. 2 show the positions of the rollers N N with relation to the feet when the arms are in their lowered position, the gentler inclines 1 of the arms lying beneath and out of contact with the keg or barrel when the latter is rolled up the abrupt incline 2 2 of the feet.

The elevator is supported at any desired height by means of the engagement of the pawls L with the ratchets K.

For racking the liquid from the barrel or keg I provide a special form of decanting device comprising a hollow cork P, preferably of rubber or other resilient material, the cork being tapering in contour to enable it to fit bungs of varying sizes. The inner open end of the cork is protected by a conical screen Q, which may be removably fitted in the open end and is pierced and supported at its upper end by a vent-pipe R of considerable length, which projects through the closed head or outer end of the cork and is provided at its outer end with a stop-cock c for regulating the admission of air to the pipe and keg. Short lengths of tubing a a are secured in and carried by the head of the cork, the inner open ends of the tubes being contained within the screened hollow chamber in the cork, the outer ends of the tubes adapted to receive lengths of hose b, by means of which they are connected with the bottles or other receptacles to be filled. In the event that all the liquid-exit tubes a a are not employed and to prevent a waste of the liquid therethrough I provide the plugs e, receivable in the outer ends of the tubes to close them.

In operation I first load the keg or barrel on the elevator and then raise it to the desired height, taking care that the bung-hole of the keg is on top. When at the desired height, the bung is removed and the cork P inserted in place thereof, the pipe R extending nearly to the bottom of the keg, which latter is then given a half-rotation or less on the rollers N N to bring the bung at the bottom or nearly so. The bottles d d may be set on a table on a plane lower than the barrel or keg preferably and being connected with the latter by means of the flexible hose b, whereupon the cock or valve c is opened to admit air to the pipe R and into the keg while the liquid contained therein flows out by gravity through the exit-tubes a a into the bottles. When it is desired to shut off the flow abruptly, the barrel or keg is rotated back to its initial position, bung uppermost.

I am aware that prior to my invention beer siphons or pipes have been used with strainers, corks, and one or more exit-pipes; also, that pipes have been used at the top or ends of a barrel to force compressed air above the liquid, the object being to force the con-

tents of the barrel out at the top. My invention more particularly involves a gravity-exit at the bottom and the introduction of atmospheric pressure into the keg.

It will also be evident that many changes or suggestions might be made in the form and arrangement of the several parts described without departing from the spirit and scope of my invention, and hence I do not wish to limit myself to the exact construction herein set forth; but,

Having thus fully disclosed my invention, what I claim as new, and desire to secure by Letters Patent, is—

1. A liquid-decanting apparatus comprising a hollow resilient cork receivable and projecting within the discharge-opening of a liquid-containing receptacle, a screen suitably received and inclosing the inner hollow end of the cork, an air-supply pipe passing through the cork and screen, the outer end of the pipe in free communication with the atmosphere, means for closing the outer end of the pipe, a discharge-tube projecting through the cork and communicating with the screened hollow chamber therein, a flexible hose removably connected with the outer end of the tube and means for closing the tube when desired.

2. As an article of manufacture, a hollow stopper open at its inner end, an air-inlet pipe passing entirely through the stopper and extending some distance beyond the inner end thereof and a delivery-tube separate from and independent of the air-inlet pipe and also passing through the stopper, the tube and pipe both received in the open interior of the stopper.

3. As an article of manufacture, a hollow stopper closed permanently at its outer end, an air-supply pipe passing through the outer closed end of the stopper, a discharge-tube also passing through the outer closed end of the stopper and a screen formed separately from the stopper and located in and covering the open inner end of the stopper, the air-pipe passing through and beyond the screen.

4. As an article of manufacture, a stopper comprising a cork open at its inner end to form a chamber within the cork, a screen engaged by the open inner end of the cork, an air-pipe projecting through the closed end of the cork and through the screen, the screen removably secured upon the pipe and a discharge-tube passing through the closed outer end of the cork, the inner end of the tube received and lying within the chamber inclosed by the cork and screen.

In testimony whereof I have signed my name to this specification in the presence of two subscribing witnesses.

ALFRED J. SIGNOR.
